DESIGN.

W. F. HELMOND.

TYPEWRITING MACHINE FRAME,
APPLICATION FILED MAR. 31, 1919.

55,381.

Patented June 1, 1920.

Inventor:
William F. Helmond
by D. B. Stickney
Attorney.

UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

DESIGN FOR A TYPEWRITING-MACHINE FRAME.

55,381.

Specification for Design.

Patented June 1, 1920.

Application filed March 31, 1919. Serial No. 286,578. Term of patent 14 years.

To all whom it may concern:

Be it known that I, WILLIAM F. HELMOND, a citizen of the United States, residing in Hartford, in the county of Hartford and State of Connecticut, have invented a new, original, and ornamental Design for a Typewriting-Machine Frame, of which the following is a specification, reference being had to the accompanying drawing, forming part thereof.

The figure is a perspective view of the frame of a typewriting machine, showing the new design.

Claim:

The ornamental design for a typewriting machine frame, as shown.

WILLIAM F. HELMOND.
